ABSTRACT OF THE DISCLOSURE

The invention relates to a method and to an apparatus for the mechanical winning of coal or other minerals occurring in seam formation by longwall mining by means of an apparatus consisting of an advanceable support framework carrying interarticulated guide rail sections for a link cutter chain carrying at the face side of the chain links in sections of the chain mineral removing elements including cutting elements for producing in the coal face a channel in advance of the face and wedge-like shaped excavation tools in rear of said cutting tools which wedge in from the channel the coal, after the channel has reached a predetermined depth so to advance the excavation face for a predetermined extent, means being provided to angularly adjust said guide rail sections with respect to the horizontal axis, so to alter the angle of attack of the cutter chain with respect to the excavation face.

Background of the invention

In the known embodiment of this method the advance of the members of the advanceable frame work and, therefore, of the guides for the cutter chain arranged thereon as well as the penetrating depth of the cutting tools, attached to the chain, into the channel which they produce running in front of the working face are limited by the fact that clearing tools, which are attached to the members of the cutter chain and for their part bear the cutting members, attach themselves flatly to the working coal face. Because in this known arrangement the thickness of the successive clearing tools which lie flatly to the working face in continuously reduced, the chain may continuously move nearer the face, in which case however the thickness of the distance pieces connecting the cutting elements to the chain and, therefore, the distance between the cutting elements, which extend into the channel, and the chain remains constant. This causes a continuous or approximately continuous advance of the support members bearing the chain and accordingly a constant bearing of the chain on the face, i.e. not only are the cutting elements which deepen the channel brought to bear against the wall of the channel about to be chipped away by them, but the clearing tools are also continuously rubbed against the coal face outside the channel, whereby the tractive force required to move the cutter chain and, therefore, the force capable of taking up the chain are substantially increased.

Summary of the invention

These difficulties and disadvantages are eliminated by the method which forms the object of the present invention. In accordance with the basic concept of the invention it is possible that not the fixed coal face, but the cutter chain guide, which is supported on the advanceable framework and is therefore itself stationary, forms the support for the cutting tools, successive tools being arranged at increasing distances from the guide and deepen the channel successively. The result of this new method makes it possible to reduce the forces of friction, but also at the same time to increase the precision of the advanc-

2

ing operation, since the advance of the cutter no longer depends on a simultaneous shifting of the framework which may for its part be subject to disturbances, and since possible unevenness on the coal face no longer influences the progress of the cutter. When the cutter chain guide is in a given position, the actual depth of the cut is always clearly determined by the distance between the cutting elements and the guide of the cutter chain, said distance being given by the thickness of the carrier members.

The invention is therefore characterized that in a coal winning process the cutting elements fixed on the chain successively in the direction of movement of the chain and their carrier elements extend from the guide in successively increasing distances in the direction of the coal face, carrier elements sliding on the chain guides which are supported on the advanceable framework. The advanceable framework remains stationary during the cut and is advanced only after the passage of the "activated" section of the chain on which the cutting elements are arranged i.e. during the passage of the following section of the chain not fitted with such tools after the deepening of the channel produced by them for a predetermined amount, by this advance. Then introducing a wedging tool fixed on the chain following the cutting elements into the channel. The wedging tool in advancing through the channel while the framework is stationary excavates the coal above or below as the case may be from the channel so as to advance the coal face as such for the deepness of the channel whereupon the next section of the chain fitted with cutting tools supported on the then stationary framework resumes the deepening of the channel and so on.

Therefore, after the sections of the cutter chain fitted with the cutting elements have deepened the channel by the provided measure in the stationary support, the members of the advanceable framework can be advanced with great precision by the action of automatically released control commands, each advancing frame of the framework covering the pre-determined path, the distance of which is determined, for example, by using measuring cylinders which accurately establish the advance path for every support member. The pressure applied to execute the advance can therefore be of any desired height, whereas in the known method it was practically limited by the fact that the forces of friction produced when the distance pieces are pressed against the coal face could not exceed a specific measure as this entailed the risk of checking the progress of the advanceable framework. In the inventive method such irregularities can easily be avoided by making the distance between the wedging tools on the cutter chain sufficiently great and by allowing a greater margin for the time intervals in which the supporting framework is advanced.

As in the known method, the clearing and the wedging tools attached to the link chain are supported on an extended flange of the rails which guide the link chain. Since the clearing tools no longer form the distance pieces between the cutter chain and the coal face, it becomes unnecessary for these clearing tools to be variably thick in design or for the guide of the cutter chain to be arranged on a certain incline to the coal face. On the contrary the guide of the cutter chain can be and is kept exactly parallel to the coal face produced by the wedging tools while the channel is deepened by the cutting tools. Only when the wedging tools and the following cutting tools have travelled through is the guide brought nearer to the new coal face. Regular operation of all the clearing tools of equal thickness is thereby ensured.

In the known method the cutting edges of the clearing tools could not be provided with a clearance angle, because the existence of such an angle would have resulted

that the tools would have penetrated the coal face since they and then would no longer have fulfilled their function as distance pieces. This aspect does not apply in the new method which therefore makes it possible to provide such a clearance angle so that the clearing tools can also cut themselves free even in the case of an irregular coal face.

Since the advanceable supports are advanced only at intervals, it is sufficient then if the frames to be advanced are braced by elastic pressure between the roof and floor only for short periods of the advance. During cutting and wedging, the framework is set with its full resistance pressure.

Since the guides of the chain are no longer continuously shifted and there is no longer a constant contact between the chain or distance pieces fitted thereon and the coal face, it would be conceivable that the space between the chain and coal face kept clear of coal by the clearing tools is, after the latter have passed through newly breaking parts of the face, filled up before the advance is resumed so that the channel cleared by small cuttings collapses again after the cutting tools have travelled through. However, in order that the extracting operation can proceed according to plan, it must be ensured that, after the clearing and cutting tools have passed through, the guides of the chain can be under any circumstances moved nearer to the face by the provided measure and therefore their extended lower flanges (extended upper flange on the roof) which each support the grooving tools can be pushed correspondingly deep into the channel. The risk that the space required for advancing may be filled up again before or even during the advance is indicated mainly in the vicinity of the floor, but is practically non-existent in the vicinity of the roof. In order to eliminate this risk a number of preventive measures are provided in accordance with the invention and they can be applied either individually or in a combination.

In simple cases it is always sufficient if the guides of the cutter chain on the roof, in contrast to those on the floor, are rearwardly staggered with respect to the guides on the floor in the direction of advance of the coal winning. This has at the same time the advantage that the caps rising above the conveyor can be shorter in design and the coal extracted from the roof falls directly into the conveyor. This possibility applies just as much to the use of a single endless cutter chain rotating parallel to the face as to the use of two cutter chains, one of which rotates parallel to the floor and the other parallel to the roof. When using a single endless cutter chain it is if need be expedient to slightly incline the axes of the driving and reversing sprockets of this chain to the floor. However, it is also possible to keep these axes exactly parallel to the floor and roof and to let the connecting guide rails of the chain on the floor run at a certain angle to the coal face and/or those on the roof run at a certain angle away from the coal face.

When using two cutter chains, one of which moves in the vicinity of the floor and the other in the vicinity of the roof, it is expedient to drive the driving wheels of both chains jointly, i.e. not to run the two chains in opposite directions but in the same direction. In this way the working flight of the roof chain, in contrast to that of the floor chain, does not need to be rearwardly staggered, since, when flights of chain are directly superposed, the wedging tools associated with the roof chain can be rearwardly staggered in the conveying direction of the chain in contrast to the wedging tools associated with the chain moving along the floor. In this way the roof requires a smaller number of clearing tools than the floor so that despite transferred wedging devices the clearing of the channels on the roof and floor respectively can be terminated simultaneously. In the case of very low seams wedging tools can be expediently and advantageously omitted on the chain which runs on the roof. However one should not dispense with cutting out a channel in front of the coal

face in the vicinity of the roof, because in every case the presence of this cutting improves the action of the wedging tools arranged on the other cutter chain. Furthermore it provides on the roof a plane for the trouble-free progress of the advanceable framework which is elastically braced between the roof and floor during the advance.

In seam conditions in which it is impossible to calculate that the wedging tools working on the floor operate up to the roof and vice versa, it is more advantageous to work with a single endless cutter chain which, together with all its associated tools, moves along the floor in one direction and along the roof in the opposite direction.

In a preferred form of the invention, while advancing the guide rail, through sections of which the chain passes, its links are gradually pushed forward until they are close to the face, the enlarged flange of the guide rail being pressed into the channel to the same extent. Clearing tools are therefore associated with the unactivated regions of the link chain and they clear the part of the channel located directly in front of the extended flange of the guide and the region directly in front of the links of the cutter chain above this flange. While the guide is pressed forward in the direction of the face by this amount, the next tool of the link chain moving along the face reaches that same point, said tool like-wise making space for a further advance.

In order to clean the channel several links of the cutter chain may be provided with a shoe, extending over the width of the lower flange of the guide rail, said flange being extended in front of the links, and extending right down to the base of the channel in front of this flange, said shoe having a shovel-like, rising surface which slides on the lower flange of the guide and on the base of the channel, and at the forward outer end of this surface the shoe has an edge, extending over the whole height of the channel and provided with a clearance angle, and connected to this edge a wall, which runs up to the chain link, encloses the shovel-like surface and extends from the surface as far as the upper limiting face of the channel, the upper end of said wall being in turn provided with a cutting edge which has a clearance angle. These clearing shoes firstly clean the part of the channel directly in front of the extended flange of the guide rail and convey the coal taken up there by the shovel-like face into the space above this extended flange. The wall enclosing the shovel-like face diverts the collected coal in the direction of the chain. Behind this wall the coal either falls down on to the extended flange or is conveyed further upward by a tool arranged on the chain link.

When advancing the extended flange the edge, which is arranged on the forward end of the clearing shoe and provided with a clearance angle, is pressed into the coal broken down. By means of its forward movement the clearance shoe cuts itself free and conveys the coal which it has grasped out of the channel. While the upper end of the wall extending as far as the upper limiting face of the channel is in turn provided with a cutting edge having angular clearance, the clearing shoe can also cut itself free along the upper limitation of the channel. When pressing the extended flange further forward the next clearing shoe can therefore penetrate correspondingly deeper into the channel and carry on its clearing accordingly.

Also the clearing tools associated with the activated sections of the cutter chain may be provided with clearing shoes which discharge the coal loosened by the cutter tools out of the channel so that the following cutter tools can further deepen the channel which has been completely cleared of the small cuttings. These clearing shoes connected to the cutting tools may be similar in design to the usual clearing shoes described, only their parts arranged above the extended flange of the guide rail being replaced by the corresponding parts of the clearing tools with which they are associated, and

their parts arranged in front of the extended flange of the guide rail not only extend over a narrow strip of the channel, but also extend over its entire width. While the normal clearing shoes are all of the same width, the clearing shoes associated with the activated sections of the cutter chain become successively wider by the same amount by which the cutting elements associated with the preceding clearing tool have deepened the channel.

The space between the links of the cutter chain and the coal face, i.e. the space above the extended flange of the guide rail which is kept clear in the activated sections of the cutter chain by the clearing tools, after the grooving tool connected to the latter has advanced the coal face, does not need to be kept constantly clear, but the bulk material which, after the activated sections of the cutter chain have travelled through, may have accumulated in the space, requires to be discharged to a degree such as this space is constricted by the further advancing of the cutter chain and its guides.

For this purpose some of the chain links not fitted with wedging or cutting tools may be provided with a narrow edge which rises in the form of a ramp from the lower flange of the guide rail, rearward over the whole length of the link and projects with angular clearance towards the coal face. The links are of normal thickness only below this edge, whereas above the edge there is a recess. This recess provides a ramp running in the direction of the edge, on which ramp the bulk material, gripped by the protruding edge cuts itself free during the advance of the chain, is guided and conveyed upwards.

With respect to the face of the links on the coal face side, the upper flange of the guide rail is displaced rearward for the width of the recess of the link arranged above the rising edge, so that two links provided with the rising edge may each follow a further link which, in the region before the upper flange of the guide rail, is provided with an extension which prolongs the ramp at least as far as the upper edge of the guide rail, said ramp like-wise having an edge projecting with angular clearance towards the face.

The successive advancing of the support framework is expediently controlled by control members which are themselves associated with the cutter chain running through the guide rail.

Since, in the case of a chain endless and rotating in the plane of the face, the cutter chain covers half of its path along the floor where the danger of the control operations, being disturbed by foreign bodies is particularly great, a control chain rotating practically synchronously with the cutter chain can for example be used advantageously for generating control impulses, the lower flight of which chain can be guided at any desired distance from the floor. The drive of this control chain is derived from the drive or drives of the cutter chain, in such a manner that corresponding links of both chains are always located in the same region of the long wall face. The idea of using a control chain which, moving along the face synchronously with the motion of an extracting device, controls the advance of the support framework or of the conveyor corresponding to the progress of the extracting operation, can also be applied to other winning devices moved, such as coal-ploughs, normal cutting machines and the like, and as such is therefore an independent feature of the invention.

An advancing cylinder may be employed, acting on the associated floor or roof cap of the advance support framework and supported on a stationary frame of the support framework, and associated with every section of the guide rail in which the cutter chain moves, and preferably supplied with a quantity of pressure fluid by the actuation of a measuring or metering cylinder connected thereto, said quantity of pressure fluid causing the guide rail to be advanced by the prescribed amount. Each measuring cylinder is actuated by shifting an associated valve,

5 whereby either the left chamber of the measuring cylinder is, for example, filled from a source of pressure fluid and at the same time the right chamber empties into the pressure cylinder or, after the shifting of the valve, the now filled left chamber empties into the pressure cylinder for advancing and the right chamber is filled from the pressure fluid source. The said valves may be shifted one after another by a control member which moves past them and is connected to each activated section of the cutter chain provided with extracting tools or to the corresponding section of the control chain.

Brief description of the drawings

15 FIGURE 1 shows a purely plan view schematic representation of a working illustrating the method, particularly the course of the guide shifting operation, and the dimensions in the longitudinal direction of the long wall face are represented as being considerably shortened in order to make it possible to show the gradual advance of the working face and the advance of the entire arrangement in as great an area of the long wall face as possible.

20 FIGURES 2 to 5 are cross-sections through the extracting apparatus in successive phases of the extracting operation according to the lines II-II, III-III, IV-IV and V-V of FIGURE 1.

25 FIGURE 6 shows a section of the chain occupied by the extracting tools as seen from the coal face.

30 FIGURE 7 is a top view of FIGURE 6 with the omission of the upper flange of the guide rail, and

35 FIGURE 8 shows a section through an outer strap of the chain along the line VIII-VIII of FIGURE 6.

Description of the preferred embodiment of the invention

40 In the drawings the coal face is denoted by 1, the channel produced therein by 2, and the rail of generally U-shape guiding the cutter chain by 3, said guide rail being provided with a forward edge 4 on its upper flange which overlaps the cutter chain guided on the floor and with a forward edge 5 on its extended lower flange, which forward edge ends on the coal face, but, during the advance and then until the new face is produced, it is pushed into the channel 2 cut into the coal face.

45 The cutter chain itself consists of outer links 6, 6' and inner links 7. The link 6' is larger in design than the link 6 and is guided through grooves between the rail flanges in order to prevent the chain from moving out of place. The members of the chain and the tools arranged thereon are not shown in FIGURE 1.

50 The outer links 6 are fastened in the activated sections of the cutter chain to a multipart wedging or grooving tool 8 (FIGURE 2) which is followed by several multipart clearing tools 9 (FIGURE 3) which have essentially the same profile. The wedging or grooving tools 8 are of the same design shown in my U.S. Patent 3,390,915. The successively arranged clearing tools are all of the same thickness and the knife 9' associated therewith has a clearance angle projecting in the direction of the coal face. The forward edge of this knife lies close to the coal face, but is not intended to penetrate into the face in the normal manner and can only cut itself free in the event of unevenness of the coal face, or during controlled movements of the rail for the purpose of altering the cutting plane. Therefore the faces of the clearing tools normally do not abut the coal face. Cutter heads 10 for deepening the channel are attached to the clearing tools. Successive

65 cutter heads associated with the same clearing tool have cutting tools 11 operating at different levels. Thus another cutter head is moved in front of the cutter head shown in FIGURE 3, the cutting tool of the first cutter head having operated at a medium level of the channel, and is followed by a further cutter head, the cutting tool of which correspondingly deepens the channel also in its uppermost area. The next clearing tool is provided with a clearing shoe (not shown) which extends over the whole width of the channel and clears it of small

cuttings. This clearing shoe in turn is followed by a set of cutting tools which penetrate deeper into the channel. The effectiveness of seven successive sets of such cutting tools can be seen in FIGURE 1 at the right end and between the sections II-II and III-III.

After the activated section of the cutter chain has advanced and deepened the channel, there then follows an unactivated section of the cutter chain designed according to FIGURES 4 to 8 at a certain distance from the face, which corresponds to the thickness of the clearing tools 9 (FIGURE 4) and after the advance into contact with the coal face (FIGURE 5). To some of the links 6 of the chain, a clearing shoe 12 is coordinated. This clearing shoe has a shovel-like face 13 sliding on the bottom of the channel and a parallel surface 13' sliding over the extended flange 5 of the guide rail. At the forward outer end of the shovel-like surface 13 is formed an edge 14 which extends over the entire height of the channel, the edge 14 being followed by an edge 15 running along the upper end of a wall 15' which encloses the shovel-like face and is provided with a support 25. The edge 15 provided with an angular clearance just like the edge 14 can be prolonged by a ramp 16 which is concurrently arranged to the rising face 13, 13' and extends across the entire height of the channel. This ramp can be seen more clearly in FIGURES 6 to 8 on the next link which is not provided with a clearing shoe. It is formed by providing the link 6 with a rising edge 17 projecting with angular clearance towards the coal face, said link being of normal thickness only in its part 26 located in front of this edge in the travelling direction of the chain and in the part 26' located below and behind this edge, while above the edge 17 the link has a recess, as can be seen particularly in FIGURE 8.

Opposite the upper flange 4 of the guide rail the links of the chain project slightly towards the coal face (approximately by the width of the ramp 16). The edge 17 forms another projection which, after the guide is advanced somewhat, which abuts against the new coal face produced by the wedging or grooving tool 8. This edge 17 grasps and conveys away coal which eventually could have accumulated after the passage of the wedging tool 8 and clearing tools 9 following the tool 8 between the chain and the coal face. The remaining sections of the chain links do not come into direct contact with the face. In order to prevent the falling down or jamming of the coal conveyed upwards over the ramp 16 between the extension 4' of the guide rail and the coal face, the inner link 7 of the chain which follows the outer link 6 provided with a ramp 16 can be provided with an upwardly directed extension 18 which has a ramp 19 which prolongates the ramp 16 at least as far as the upper edge of the extension 4' the ramp 19 being for its part provided with an edge 20 projecting towards the coal face.

In operation corresponding to the progress of the cutter chain, the schematic representation in FIGURE 1 shifts to the right with the progress of the wedging and clearing tools, the advance of the coal face and the progress of the deepening of the channel the advance of the advanceable support framework with the guide rails supported by it progresses one by one in automatically controlled manner. The frames which were in advanced position are then in rear at the end of the advance of the following frame, the oblique part of the guide rails seen in the middle of FIG. 1 being shifted to the right parallel to itself approximately at the same pace as the cutter chain.

There is incorporated in this application by reference applicant's prior U.S. Patent 3,390,915, dated July 2, 1968, showing and describing the support framework for the guide rails which in turn receive the cutter chain for the tools. Thus, such structure as well as the mechanism for advancing same, is incorporated by reference in this application.

What I claim is:

1. A method for the mechanical extraction of coal 75

- and other minerals by longwall mining by means of an apparatus consisting of an advanceable support framework carrying interarticulated guide rail sections for a link cutter chain with means for angularly adjusting said guide rail sections with respect to the horizontal axis to alter the angle of attack of said cutter chain with respect to the excavation face, wedge-like mineral removing elements carried at the face side of links or groups of links of the chain and cutting elements for producing a channel in advance of the coal face arranged on other links or groups of links as well as clearing tools fixed on the cutter chain, said chain having sections in which such tools are absent, the wedgelike elements excavating the coal from the channel supporting themselves in the channel, after the latter has reached a predetermined depth for advancing the excavation face a predetermined extent, characterized in that the cutting elements fixed on the chain following one another in the direction of movement of the chain respectively, carrier elements for said cutting elements extending from the guide in successively increasing distances in the direction of the coal face and sliding on the chain guides supported on the advanceable framework, said framework remaining stationary during the cutting out of the channel, the guides for the chain together with the framework being advanced for a predetermined distance after the passage of a section of the chain fitted with cutting tools and by this advance introducing a wedging tool fixed on the chain following the cutting elements into the channel for performing the excavating phase to advance the coal face as such for the deepness of the channel whereupon the next section of the chain fitted with cutting tools supported on the now again stationary framework resumes the deepening of the channel and so on.
2. A method as claimed in claim 1 in which a channel is simultaneously produced in the roof and in the floor region of the coal face, characterized in that the channel in the roof area is staggered in rearward direction with respect to the channel produced in the floor area by correspondingly staggering the guiding rails of the chain.
3. A method according to claim 1 characterized therein that the advance of the supporting framework is automatically controlled in dependency upon the movements of the chain.
4. An apparatus for mechanically winning of coal or other minerals by longwall comprising at least one chain running in the area of the roof and of the floor and guided in angularly adjustable rail sections with respect to the horizontal axis which sections are attached to the framework of an advanceable support framework, said chain comprising sections in which channel cutting tools are attached to the chain preceded by wedge-like acting excavating tools and sections of the chain in which tools are absent, the cutting tools being attached to the chain by carrier members in successively increasing distances from the chain.
5. Apparatus as claimed in claim 4 characterized therein, that the carrier members form themselves clearing tools for the channel and for the space between the coal face and chain.
6. Apparatus as claimed in claim 4 comprising a control chain associated with the cutter chain running practically synchronously therewith and serving to generate impulses which control the advance of the framework supporting the guides of the chain.
7. Apparatus as claimed in claim 4 characterized therein, that as well in the area of the roof as in the area of the floor a chain runs in the plane of the seam and arranged parallel to the floor and the roof, driving sprockets for both of the chains, and a common drive for said sprockets.
8. Apparatus as claimed in claim 7, in which the guides of the cutter chain on the roof are arranged to pivot oppositely to those of the cutter chain on the floor.
9. Apparatus as claimed in claim 4 comprising U-

shaped chain guides arranged with the web in the plane of the coal face, the guides acting as a tool carrier, at least some of the chain links of the said intermediate chain sections having edges which rise in the form of ramps from the lower flange of the guide diagonally and backwards over the whole height of the link and project with angular clearance towards the coal face, said links being of their normal thickness only below the edges, but having recesses above the edges.

10. Apparatus as claimed in claim 9, wherein the forward edge of the upper flange of the guide opposite the face of the links on the coal face side is reversed by the width of the recess of the links arranged above the rising edge,

11. Apparatus as claimed in claim 9, wherein several links, which are provided with a ramp formed by the rising edge and the recess of the links, are followed by another link having an extension ramp edge continuing

the preceding rising ramp edge at least as far as the upper edge of the guide rail, the ramp of the extension having an edge which projects with angular clearance towards the face.
